PROCESS FOR BREAKING PETROLEUM EMULSIONS

Melvin De Groote, St. Louis, and Bernhard Keiser,
Webster Groves, Mo., assignors to Tretolite
Company, Webster Groves, Mo., a corporation
of Missouri

No Drawing. Application January 6, 1934,
Serial No. 705,616

9 Claims. (Cl. 196—4)

This invention relates to the treatment of emulsions of mineral oil and water, such as petroleum emulsions, for the purpose of separating the oil from the water.

- 5 Petroleum emulsions are of the water-in-oil type, and comprise fine droplets of naturally-occurring waters or brines, dispersed in a more or less permanent state throughout the oil which constitutes the continuous phase of the emulsion.
- 10 They are obtained from producing wells and from the bottoms of oil storage tanks, and are commonly referred to as "cut oil", "roily oil", "emulsified oil", and "bottom settling".

The object of our invention is to provide a novel, inexpensive and efficient process for separating emulsions of the kind referred to into their component parts of oil and water or brine.

Briefly described, our process consists in subjecting a petroleum emulsion of the water-in-oil type, to the action of a treating agent or demulsifying agent of a particular kind or composition hereinafter described, thereby causing the emulsion to break down and separate into its component parts of oil and water or brine, when the emulsion is permitted to remain in a quiescent state after such treatment, or equivalent separatory procedure.

The treating agent or demulsifying agent used in our process consists of fatty sulfonic acids or their salts or esters, characterized by the fact that the sulfonic acids are of the type corresponding to the general formula:

35 in which R and R' are aliphatic radicals or substituted aliphatic radicals, for instance, an aliphatic radical having a hydroxy or carboxyl group, and X is a hydroxyl radical or a halogen. 40 Such sulfonic acids may be derived from unsaturated fatty acids or fats, such as oleic acid, olive oil, neatsfoot oil, linoleic acid, fatty acids derived from fish oil, and the like. Likewise, 45 such sulfonic acids may be derived from ricinoleic acid or castor oil, if the sulfonating agent employed is in ample excess of the amount necessary for sulfonation of the alcoholiform hydroxyl.

We are aware of the fact that fatty sulfonic acids are members of a class of materials known as modified fatty acids, and that said modified fatty acids are used extensively in the demulsification of cut or emulsified oil. Also that sulfo fatty acids or salts or esters thereof have been in extensive use for a long time for breaking cut oil emulsions. Such sulfo acids included as their

most important members, fatty acid sulfates and fatty sulfonic acids, as described in Industrial & Engineering Chemistry, Analytical Edition, Volume 3, page 243 (1931).

The structural formula for oleic acid may be written as follows:

Ordinary oleic acid is characterized by the fact that the unsaturated bond (ethylene linkage) occurs between the ninth and tenth carbon atom, when one considers the carboxyl carbon atom as the first one. When sulfuric acid or, more preferably, sulfuric acid monohydrate, reacts with oleic acid at relatively low temperatures, such as 15° C., there is formed a fatty acid sulfate by saturation of the unsaturated bond. This material is indicated by the following formula:

20

If sulfonation takes place at or near the boiling point of water, it has been believed that there is formed a sulfonic acid, as shown by the following formula:

25

(See Fats, Natural and Synthetic, Myddleton & Barry, Benn, 1924, page 57.)

The manufacture of fatty sulfonic acids, intended to be employed as catalysts in the hydrolytic splitting of fats, was originally disclosed in U. S. Patent No. 601,603, to Twitchell, dated March 29, 1898. These materials, so produced according to the disclosure of said Twitchell patent, are recognized as being saturated sulfonic acids, because they have no iodine value; do not decompose on boiling with dilute hydrochloric acid; and give sulfites on fusion with caustic soda or caustic potash. Due to their analogy to fatty acid sulfates, sometimes referred to as fatty esters, or even as fatty acid esters, and whose composition and structure is well known, these Twitchell fatty sulfonic acids, are frequently held to be of the composition and structure as indicated by the above formula and reference to Myddleton and Barry. However, Twitchell, Journal of the Society of Chemical Industry, Volume 36, page 179 (1917), indicated that such a simple formula probably did not represent the actual facts, and that the material itself was an ester acid type of body, as differentiated from the simpler formula previously described, and frequently accepted, especially for purposes of com-

parison, with fatty acid sulfates, or with sulfonic acids in which the sulfonic acid radical is not attached to either the ninth or tenth carbon atom.

U. S. Patent No. 1,931,491, dated October 24, 1933, to Haussmann, describes the manufacture of fatty sulfonic acids derived from unsaturated fatty acids at low temperature and under certain peculiar conditions. Sulfonic acids so obtained and until recently unknown, have a composition which is in agreement with the formula proposed by Myddleton and Barry, in 1924, v. s., for fatty sulfonic acids produced at or near the boiling point of water, as first described by Twitchell. If one produces sulfonic acids according to the method described in said recent U. S. Patent No. 1,931,491, and then purifies said sulfonic acids from unsulfonated fatty material, fatty sulfates, free sulfuric and hydrochloric acids, and the like in the conventional manner, such as the method of purifying fatty acid sulfates described in U. S. Patent No. 1,894,759, dated January 17, 1933, to De Groote and Wirtel, then one obtains a relatively pure fatty sulfonic acid which is different in appearance and in chemical constants from the purified fatty sulfonic acid derived by action of sulfuric acid on the fatty body at or near the boiling point of water. Careful investigation reveals that fatty sulfonic acids produced in the manner described in U. S. Patent No. 1,931,491, previously referred to, conform in ultimate composition and in properties to the formula previously given by Myddleton and Barry for the older type of fatty sulfonic acids made at the boiling point of water. Further examination of fatty sulfonic acids made near the boiling point of water confirms that such materials represent an ester type of compound. Thus, one concludes that the earlier suggestion of Twitchell is correct, and that sulfonic acids of the type recently disclosed in U. S. Patent No. 1,931,491 are sub-

fication by action of these true sulfonic acids in the forms of acids, salts, or esters than by any other available reagent. The present invention contemplates the use of such true sulfonic acid bodies for breaking oil field emulsions, and is an improvement on prior processes employing demulsifying agents of the kind known or available before the date of said Haussmann patent.

The manufacture of reagents, intended for use as the demulsifying agent of our process, is described completely in U. S. Patent No. 1,931,491, previously referred to. We prefer to prepare our reagent demulsifying agent in the following manner:

140 pounds of chlorsulfonic acid are added to 15
100 pounds of ethyl ether, while suitable cooling
means are being applied so as to hold the tem-
perature under 10° C. 282 pounds of oleic acid
are gradually added, and the temperature is then
raised to about 20° C. During the reaction it is
advisable to remove from the mixture any hy-
drogen chloride that may be formed. One suit-
able procedure is to pass a dry current of air,
which has been saturated with ether, through
the reaction mixture. At the end of 24 hours the
sulfonation mass is poured into water, and the
ether is eliminated by heating. A sulfonated
oleic acid of the composition above referred to
and which is soluble in water and stable towards
acids, is obtained. A washing process is em-
ployed to remove the excess of inorganic acid.
The fatty product contained in the upper layer
is neutralized with strong ammonia to the methyl
orange indicator end point, so that the acid hy-
drogen of the sulfonic group is completely re-
placed. Obviously, the lower waste acid layer is
withdrawn before neutralization. An equivalent
amount of propyl ether may be employed instead
of ethyl ether. The reaction apparently proceeds
according to the following equations:

55 substantially new compositions of matter, notwithstanding the suggestion of Myddleton and Barry in 1924, because the product described by Myddleton and Barry is not a sulfonic acid of the type indicated by their proposed formula. Presumably Myddleton and Barry intended this formula solely for purpose of comparison with fatty acid sulfates and not as an indication of ultimate composition.

60 position.
We refer to these fatty sulfonic acids of the kind described in U. S. Patent No. 1,931,491 as true fatty sulfonic acids. We have found that these true sulfonic acids are very effective treating agents for breaking many oil field emulsions. In some instances, emulsions may be broken more readily by fatty acid esters of sulfuric acid or by some other type of sulfonic acid, for instance, the older Twitchell type of ester acid sulfonic acid or 65 the more recent type of sulfonic acid described in U. S. Patent No. 1,926,715, dated September 12, 1933, to De Groote, Keiser and Wirtel. Some emulsions may be more susceptible to treatment by fatty aromatic sulfonic acids, but in any event 70 certain emulsions are more susceptible to demulsi- 75

Briefly described, the method of producing these true fatty sulfonic acids intended to be used in our process, comprises acting with an "onium" compound of a sulfonating agent stronger than concentrated sulfuric acid on the unsaturated fatty acid or fatty acid compound, under conditions so that the quantity of sulfonating agent is greater than one molecular proportion per molecular proportion of the fatty body, if the latter contains a hydroxyl group, as in the case of ricinoleic acid or castor oil. "Onium" compounds represent a group of organic compounds of the type RXH_y which are isologs of ammonium and contain the element X in its highest positive valency. R is an aliphatic radical. Isologs, of course, represent any member of a series of compounds of similar structure, but having different atoms. However, as to the actual structural formation of "onium" compounds, there is still question. Various structures, for example, have been ascribed to "oxonium" compounds, a variety of "onium" compounds. They may be considered as an addition compound or double compound of an organic oxide with strong acids (HCl , $HClO_3$) or its salts ($SnCl_4$). They

were at first considered to have tetravalent oxygen (as in a) and later trivalent oxygen, co-ordinately combined (as in b). They are analogous to ammonium salts.

In studying the reaction between ethyl ether and chlorsulfonic acid, one may be helped to understand the reaction involved if one considers the type (a) formula suggested for the oxonium compounds as more nearly representing what actually takes place in these particular reactions, especially the one involving ethyl ether and chlorsulfonic acid.

Thus, it has been found that true sulfonic acids can be produced from unsaturated fatty acids or their derivatives or mixtures thereof, in a simple manner by treating said fatty acids and the like with sulfonating agents stronger than sulfuric acid, which are reduced in their activity, as, for example, by esterification, or by formation of a so-called "onium" compound, such as the oxonium compound previously described. Thus, sulfonation can be performed either with sulfonating agents such as chlorsulfonic or pyrosulfuric acid in the presence of such compounds which are known to form therewith additive or other compounds of the type mentioned, or with esters of chlorsulfonic acid or substances furnishing the same, which substances are sometimes referred to as compounded sulfonating agents.

As examples of substances furnishing the aforesaid additive or other products with the sulfonating agents may be mentioned, for example, diethyl sulfide, diethyl ether, acetic methyl ester, diethylene oxide, pyridine and the like. In some cases the sulfonation is accompanied to some degree by another kind of substitution of the initial materials, for instance, the formation of a sulfonic acid containing chlorine, for example, when tetrahydrobenzene is treated with chlorsulfonic acid in the presence of ether. In such cases the halogen may, if desired, be easily removed, or replaced by other equivalent groups, by treatment with chemical agents such as water, alkalies, amines and the like.

These true fatty sulfonic acids may be used as such for breaking petroleum emulsions, but it is preferable that they be used after neutralization with a basic material or after esterification with alcohol. Suitable bases for neutralization may be alkaline compounds of sodium, potassium, or ammonium. In some instances the calcium or magnesium salts formed by reaction with calcium or magnesium hydroxide or carbonate show marked water solubility and sometimes even oil solubility. In either event, they are suitable for use. Various aliphatic, aromatic, and cyclic alcohols are suitable for esterification, including ethyl, methyl, propyl, etc. The esters thus formed may be water-soluble or oil-soluble. In some instances, it may be desirable to neutralize the hydrogen of the sulfonic radical, but not the hydrogen of the carboxyl radical. Amines may be employed for neutralizing the true sulfonic acids, as in the case of triethanolamine. The amine or ammonium salts are considered as being the equivalent of metallic salts. One acidic hydrogen may be replaced by one metal atom or by a radical, and

the other acidic hydrogen may be replaced by some other substituent.

In a general way, it has been stated that the formula and structure of these true sulfonic acids is as follows:

in which R and R' are aliphatic radicals, derived from unsaturated fatty acids, one of which contains a carboxyl group. The formula thus given is not intended to mean that only one single isomeric form may be used. In other words, the groups R and R' may be reversed. The carboxyl group may be attached to either R or R'. The formula is intended to conform to the composition and general structure of the true sulfonic acid only. The formula might thus be rewritten:

to indicate that the aliphatic radical R' in reality represents the aliphatic radical R'' plus the conventional carboxyl group. As previously stated, the carboxyl group might be attached to the aliphatic radical constituting R instead of R', as shown. Such a true sulfonic acid is essentially a dibasic acid. Both the acidic hydrogen of the sulfonic acid radical and the acidic hydrogen of the carboxyl radical may be replaced by a metallic atom, such as a sodium atom or an amine radical or an alcohol radical, such as an ethyl radical, etc. Thus, the formula may be rewritten:

in which Z may be an acidic hydrogen atom, or it may be a metal or an amine residue or radical or an alcohol residue as in the case of an ester. Thus, the expression "sulfonic acid radical" is intended to include not only the acid itself, but the salt, ester, or amine derivative thereof. Likewise, the expression "carboxyl radical" is intended to include not only the free acid, but also the salt, ester, or amine derivative thereof. Z represents the acidic hydrogen equivalent.

It is not necessary that the true fatty sulfonic acids as such or in the form of salts and esters be separated from accompanying fatty material or small amounts of solvent, such as ether, which may remain in the finished product. The presence of small amounts of uncombined acid or fatty acid esters of sulfuric acid are not objectionable.

These materials may be employed alone or in combination with other recognized demulsifying agents, such as water softeners, other modified fatty acids, salts of petroleum sulfonic acids, alkylated aromatic sulfonic acids, derivatives of polybasic carboxy acids, and the like.

It is understood that the term "true fatty sulfonic acid body", as herein used, should not be interpreted as referring only to the true sulfonic acids in their acidic state, but is intended to include the salts and esters just as well. In describing these true fatty sulfonic acid bodies as containing an aliphatic radical, it is obvious, of course, that such radical is not limited to unsubstituted hydrocarbon radicals, but may include some other radical such as a hydroxy radical as part of the substituted aliphatic radical.

In practising our process, a treating agent or demulsifying agent of the kind above described may be brought in contact with the emulsion to be

treated in any of the numerous ways now employed in the treatment of petroleum emulsions of the water-in-oil type with chemical demulsifying agents, such, for example, as by introducing the treating agent into the well in which the emulsion is produced; introducing the treating agent into a conduit through which the emulsion is flowing; introducing the treating agent into a tank in which the emulsion is stored; or introducing the treating agent into a container that holds a sludge obtained from the bottom of an oil storage tank. In some instances, it may be advisable to introduce the treating agent into a producing well in such a way that it will become mixed with water and oil that are emerging from the surrounding strata, before said water and oil enter the barrel of the well pump or the tubing up through which said water and oil flow to the surface of the ground. After treatment, the emulsion is allowed to stand in a quiescent state, usually in a settling tank, and usually at a temperature varying from atmospheric temperature to about 200° F. so as to permit the water or brine to separate from the oil, it being preferable to keep the temperature low enough to prevent the volatilization of valuable constituents of the oil. If desired, the treated emulsion may be acted upon by one or more of the various kinds of apparatus now used in the operation of breaking petroleum emulsions, such as homogenizers, hay tanks, gun barrels, filters, centrifuges, or electrical dehydrators.

The amount of treating agent that may be required to break the emulsion may vary from approximately 1 part of treating agent to 500 parts of emulsion, up to 1 part of treating agent to 20,000 or even 30,000 parts of emulsion. The proportion depends on the type of emulsion being treated, and also upon the equipment being used, and the temperature employed. In treating exceptionally refractory emulsions of the kind known as "tank bottoms", and "residual pit oils", the ratio of 1:500, above referred to, may be required. In treating fresh emulsions, i. e., emulsions that will yield readily to the action of chemical demulsifying agents, the ratio of 1:30,000, above referred to, may be sufficient to produce highly satisfactory results.

In general, we have found that for an average petroleum emulsion, a ratio of 1 part of treating agent to 10,000 parts of emulsion will usually be found to produce commercially satisfactory results.

Having thus described our invention, what we claim as new and desire to secure by Letters Patent is:

1. A process for breaking petroleum emulsions of the water-in-oil type, which consists in subjecting the emulsion to the action of a demulsifying agent produced by reaction between a compounded sulfonating agent obtained by reaction between chlorsulfonic acid and ethyl ether, and oleic acid at a relatively low temperature, followed by a conventional washing procedure with water, and neutralization of the fatty material

with strong ammonia until the product is neutral to methyl orange indicator.

2. A process for breaking petroleum emulsions of the water-in-oil type, which consists in subjecting the emulsion to the action of a demulsifying agent produced by reaction between a compounded onium sulfonating agent derived from a sulfonating agent stronger than concentrated sulfuric acid and an unsaturated fatty body at a relatively low temperature.

3. A process for breaking petroleum emulsions of the water-in-oil type, which consists in subjecting the emulsion to the action of a demulsifying agent produced by reaction between a compounded onium sulfonating agent derived from chlorsulfonic acid and an unsaturated fatty body at a relatively low temperature.

4. A process for breaking petroleum emulsions of the water-in-oil type, which consists in subjecting the emulsion to the action of a demulsifying agent produced by reaction between a compounded onium sulfonating agent derived from chlorsulfonic acid and an unsaturated fatty acid at a relatively low temperature.

5. A process for breaking petroleum emulsions of the water-in-oil type, which consists in subjecting the emulsion to the action of a demulsifying agent produced from chlorsulfonic acid by reaction between a compounded onium sulfonating agent and oleic acid at a relatively low temperature.

6. A process for breaking petroleum emulsions of the water-in-oil type, which consists in subjecting the emulsion to the action of a demulsifying agent produced by reaction between a compounded onium sulfonating agent derived from chlorsulfonic acid and ether, and oleic acid at a relatively low temperature.

7. A process for breaking petroleum emulsions of the water-in-oil type, which consists in subjecting the emulsion to the action of a demulsifying agent in the form of a salt, produced by reaction between a compounded onium sulfonating agent derived from chlorsulfonic acid and ether, and oleic acid at a relatively low temperature.

8. A process for breaking petroleum emulsions of the water-in-oil type, which consists in subjecting the emulsion to the action of a demulsifying agent in the form of a water-soluble salt, produced by reaction between a compounded onium sulfonating agent derived from chlorsulfonic acid and ether, and oleic acid at a relatively low temperature.

9. A process for breaking petroleum emulsions of the water-in-oil type, which consists in subjecting the emulsion to the action of a demulsifying agent, in the form of an ammonium salt, produced by reaction between a compounded onium sulfonating agent derived from chlorsulfonic acid and ether, and oleic acid at a relatively low temperature.
